PERMANENT WAVE LOTION

David Oliva, Homestead, Fla.

No Drawing. Application July 23, 1953,
Serial No. 369,960

11 Claims. (Cl. 132—7)

1

The present invention relates to a new permanent wave lotion which is particularly successful in connection with the waving of human hair, but may also be used for conditioning all fibre material, notably, animal hair, cotton, rayon, as well as natural and synthetic fibres and textile fibres and twines.

The primary object of the invention is to provide a wave lotion in which the permanence of the wave will be substantially enhanced, especially against the deleterious effects of shampooing, and will be resistant to weather conditions.

Another object of the invention is to provide a permanent wave lotion which holds the electrostatic activity of the hair to a minimum thus making it easier to comb and brush the hair without having it entangle and fly loosely about, which action of the lotion is maintained after repeated washing.

An additional object of the invention is to provide a wave lotion which will impart a sheen to the hair, which sheen is retained by the hair after repeated washing.

It is a further object of the invention to produce a wave which will closely simulate a natural wave, said wave being retained despite repeated washing and brushing and being resistant to weather conditions.

Still another object of the invention is to provide a lotion capable of achieving the foregoing objects, which lotion will leave the hands of an operator applying the same smooth and nice appearing, and which will not injure the hair or scalp to which it is applied.

As will be appreciated, the wave lotion of this invention possesses many advantages including the further attribute that hair treated with the lotion has increased resistance to heat to thereby provide increased protection against overheating when heat is employed to speed the waving operation.

In accordance with the present invention, an alkaline permanent wave lotion is provided containing as its essential waving ingredients, a proteinaceous material together with a polyalkylene glycol having at least 400 and preferably at least 1000 recurring groups in the molecule. It has been found that the inclusion of each of the aforementioned ingredients is essential to the formation of an excellent wave which is resistant to removal by washing and brushing.

Polyalkylene glycols have previously been disclosed for use in permanent wave lotions to provide a dressing effect upon the hair in place of oils which were previously used for this purpose.

As is known, this dressing effect is easily removed by shampooing and provides no lasting action.

Proteinaceous materials have also been proposed for use in permanent wave lotions. Such materials do not, without the concurrent presence of a polyalkylene glycol in accordance with the present invention, provide a fully satisfactory wave, and the proteinaceous material which is deposited upon the hair by the lotion is not resistant to brushing or washing.

I have made the surprising discovery that by the use of a polyalkylene glycol having at least 400 and preferably at least 1000 recurring groups in the molecule together with a proteinaceous material in an aqueous alkaline medium capable of softening the hair to permit waving thereof and capable of disrupting the disulfide bonds of the cystine of the hair, that an excellent wave may be formed which accomplishes the objects of the present invention. It is particularly surprising, and it could not be predicted, that the presence of the polyalkylene glycol would permit the proteinaceous material to form a wave of the excellence actually achieved, that the presence of the proteinaceous material would render the polyalkylene glycol resistant to removal by shampooing or that the presence of both ingredients would yield a wave resistant to brushing and washing.

With regard to the aqueous alkaline medium employed it is preferred to employ a mixture of two alkaline ingredients. The first of these is ammonia either in the form of a water solution thereof or in the form of ammonium carbonate. Mixtures of both may also be employed. It has been found that ammonia is particularly efficacious in softening the hair to permit its being shaped. Ammonia is, of course, a volatile material and escapes from the solution during the waving operation, such escape being hastened by heat. The second alkaline material employed is sodium or potassium carbonate. Such materials hydrolyze in water to form the corresponding hydroxides, and as will be apparent, the presence of ammonia either in the form of the hydroxide or the carbonate, prevents the completion of the hydrolysis reaction. As is well known, the alkalies such as sodium and potassium hydroxide attack the cystine of the hair and disrupt the disulfide bonds therein.

The lotion of the present invention is in the nature of a buffer solution, the development of excess alkalinity being prevented by the presence of the proteinaceous material which act as acids in a strongly alkaline medium and in such me-

dium react with the sodium or potassium ions present to form salts.

Polyethylene glycol is the preferred polyalkylene glycol for use in the present invention. A polyethylene glycol having 400 recurring groups (ethoxy groups) to the molecule is usable in accordance with the invention. The wave produced by polyethylene glycol 400 is weak and more acceptable waves are produced when polyethylene glycol of higher average molecular weights are employed. It is preferred to employ polyethylene glycols having at least 1000 recurring groups to the molecule and best results have been obtained using from 4000 to 6000 recurring groups in the polyethylene glycol molecule.

It is not essential to the invention that the recurring group in the polyalkylene glycol molecule be an ethoxy group in polyethylene glycol. Approximately equivalent results are obtained using the same number of recurring groups when the group which recurs is a propoxy (polypropylene glycol) or a butoxy (polybutylene glycol) group.

The proteinaceous material in accordance with the invention is preferably casein. It is stressed, however that a wide variety of other proteinaceous materials act in the same manner as casein, although of the many tried, casein provided the most satisfactory results with respect to the excellence of the wave.

Accordingly, the proteinaceous material employed may be any water or alkali soluble protein or aqueous alkali soluble protein, among the most important of which are yeasts of any type, any kind of animal flesh prepared so as to be soluble, powdered stomach U. S. P., mucins, blood albumen, egg albumen, sericin from silk, gelatin, cocoanut juice, cheese of any kind, powdered and liquid milk, botanein B, and bacteria. Other protein compounds and derivatives may be used such as hydrolyzed proteins, chemically reduced proteins, proteins reduced to their amino acids, enzyme digested proteins, gum karaya, gum tragacanth, gum acacia, glutins, prolamines, etc.

Preferably, the proteins employed are soluble in water or dilute aqueous alkaline solution.

The proteinaceous materials of the invention are normally effective when employed in small amounts. For example, casein is preferably employed in amounts not greater than 1 to 3%. Normally, between .25% to 20% denotes the complete range of utility and it is normally preferred to employ between 1 and 3%. As previously mentioned, casein has been found to be the most desirable of the proteinaceous materials for employment in the invention and the best results using this material are obtained employing about 1%. As the amount of proteinaceous material in the lotion is increased within the operational range, there is a tendency for the lotion to become unduly thick and, hence, unmanageable. Such unduly thick solutions can be readily thinned by the addition of 0.5% to 5% of urea.

With respect to the poly-alkylene glycol, this material may be employed in amounts of about .25% to 25%, between 3 and 10% being preferred.

The sodium or potassium carbonate is employed in amounts of between about .25% to 10%, it being preferred to employ between 1 and 2%.

With respect to the proportion of ammonia water, it has been found satisfactory to employ about 1 to 20% of a solution having a concentration of 26 to 28% in conjunction with about 1 to 20% of ammonium carbonate. When using ammonia water alone, it is preferable to use about

25%. When employing ammonium carbonate alone, it is preferred to employ about 20%.

The lotion so formed is employed by impregnating the hair to be waved with the lotion. The ammonia is then allowed to volatilize and the hair is then curled as by winding upon rollers. The curled hair is then allowed to remain in its curled position to permit the remaining ingredients in the lotion to act upon the hair. When heat is not employed to speed the action of the lotion, about 24 hours are required to permit the lotion to exert its action. When heat is employed, the ingredients in the lotion will usually complete their action within about eight minutes. The curlers are then removed and the hair rinsed with an acid rinse of a water solution of acetic acid or an acid compound in water such as aluminum acetate. The hair is then washed to remove the acid rinse.

In addition to the ingredients above mentioned, there may be added to the lotions of the invention, reducing agents such as sodium sulphite, a monoethanolamine sulphite, or oxidizing agents such as iron, peroxides where it is necessary to produce a tighter curl.

It is recognized that usually after hair has been waved with one of the conventional lotions, it is not possible to use other lotions successfully. In the case of the present invention, however, the lotion can be safely and effectively used without preliminary hair treatments or without waiting for the previously applied lotion to lose its activity.

While this invention is particularly directed to the treatment and improvement of human hair, it is also useful for the processing of animal and vegetable fibers, notably, wool and animal hair, such as camel's hair, mohair, cotton, rayon, etc.

Example 1

	Parts
40 Rennet casein	1
Potassium carbonate or sodium carbonate	1
Polyethylene glycol (4,000)	5
Ammonia water (28%)	12 1/2
45 Ammonium carbonate	9.375
Sufficient water to make 100 parts.	

To form this lotion, disperse the casein in 25 parts of water, add the ammonia water, the ammonium carbonate and the potassium or the sodium carbonate. 5 parts of polyethylene glycol is then dissolved in the mixture, and sufficient water is added to make 100 parts.

Example 2

55 The lotion of Example 1 may be employed as two separate solutions as follows:

Solution No. 1.—1 part of casein, 5 parts polyethylene glycol (4,000) and 1 part of sodium or potassium carbonate is dissolved in sufficient water to form 50 parts of solution. This solution is then applied to the hair as a hair treatment or hair conditioner. It may be dried on the hair or left in the wet condition.

Solution No. 2.—This second solution contains the remaining ingredients of the formula as follows:

Ammonia water (28%)----- 12.5 parts} either
Ammonium carbonate ----- 9.375 parts} or both
Water sufficient to make 50 parts solution.

Solution No. 2 is applied to the hair already saturated with Solution No. 1. The hair is then wrapped around a curling rod and the wave therein produced in the same manner as previously illustrated with respect to the lotion of Example 1.

Example 3

Example 1 was repeated with polyethylene glycol (400) in place of polyethylene glycol (4,000). A curl of excellent sheen and softness was obtained and the hair so waved had no split ends. The curl obtained, however, was weak.

Example 4

Example 1 was repeated using polyethylene glycol (1,000) in place of polyethylene glycol (4,000). A soft springy curl of great elasticity was obtained possessing excellent sheen and no split ends.

Example 5

Example 1 was repeated using polypropylene glycol (4,000) in place of polyethylene glycol (4,000). A curl was obtained having increased coarseness and roughness. The sheen produced was less pronounced.

Example 6

Example 1 was repeated using yeast in place of casein. The curl obtained using the lotion so modified possessed fair elasticity. Its softness was increased, but the hair possessed less body.

Example 7

Example 1 was repeated using cocoanut amino acids and a curl similar to the curl of Example 6 was obtained.

Example 8

Example 1 was repeated using botanein B in place of casein and a tight curl of reduced sheen was obtained.

The present application is a continuation-in-part of my application Serial No. 111,773, filed August 22, 1949, now abandoned.

I claim:

1. A permanent wave lotion comprising a proteinaceous material and a polyalkylene glycol having at least 400 recurring groups in the molecule in an aqueous alkaline medium capable of softening hair and disrupting the disulfide bonds of the cystine thereof.

2. A permanent wave lotion as recited in claim 1 in which said aqueous alkaline medium comprises at least one volatile alkaline material selected from the group consisting of ammonia and ammonium carbonate, together with at least one material selected from the group consisting of sodium and potassium carbonate.

3. A permanent wave lotion comprising between 0.25 and 20.0% by weight of a proteinaceous material and between 0.25 and 25.0% by weight of a polyalkylene glycol having at least 400 recurring groups in the molecule in an aqueous alkaline medium capable of softening hair and disrupting the disulfide bonds of the cystine thereof.

4. A permanent wave lotion as recited in claim 3 in which said aqueous alkaline medium comprises at least one volatile alkaline material selected from the group consisting of ammonia and ammonium carbonate, together with from 0.25 to 10% by weight of at least one material selected from the group consisting of sodium and potassium carbonate.

5. A permanent wave lotion as recited in claim 4 in which about 1.0 to 20.0% by weight of a 26 to 28% solution of ammonia water is employed in conjunction with from 1.0 to 20.0% by weight of ammonium carbonate.

6. A permanent wave lotion comprising be- 75

tween 0.25 and 20.0% by weight of a proteinaceous material and between 0.25 and 25.0% by weight of a polyethylene glycol having at least 400 ethoxy groups in the molecule in an aqueous alkaline medium containing at least one volatile alkaline material selected from the group consisting of ammonia and ammonium carbonate, together with at least one material selected from the group consisting of sodium and potassium carbonate.

7. A permanent wave lotion as recited in claim 6 in which said proteinaceous material is casein.

8. A permanent wave lotion comprising between 1.0 and 3.0% by weight of a proteinaceous

15 material soluble in aqueous medium and between 3.0 and 10.0% by weight of a polyethylene glycol having at least 1,000 ethoxy groups in the molecule in an aqueous alkaline medium containing at least one volatile alkaline material selected from the group consisting of ammonia and ammonium carbonate, together with from 1.0 to 2.0% of at least one material selected from the group consisting of sodium and potassium carbonate.

20 9. A permanent wave lotion comprising about 1.0% by weight of casein, between 3.0 and 10.0% by weight of a polyethylene glycol having between 4000 and 6000 ethoxy groups in the molecule in an aqueous alkaline medium containing from 1.0 to 20.0% by weight of a 26 to 28% solution of ammonia water together with from 1.0 to 20.0% by weight of ammonium carbonate and from 1.0 to 2.0% by weight of at least one material selected from the group consisting of sodium and potassium carbonate.

25 10. The method of treating hair which comprises subjecting the same to a lotion comprising a proteinaceous material and a polyalkaline glycol containing at least 400 recurring groups in the molecule in an aqueous alkaline medium capable of softening hair and disrupting the disulfide bonds of the cystine thereof, heating the hair and thereafter rinsing the hair with an acid rinse.

30 40 11. The method of treating hair which comprises subjecting the hair to an aqueous solution of a proteinaceous material, a polyalkaline glycol containing at least 400 recurring groups in the molecule and an alkali, then subjecting the so treated hair to an aqueous solution of at least one volatile alkaline material selected from the group consisting of ammonia and ammonium carbonate, heating the hair and thereafter rinsing the hair with an acid rinse.
